MASSAGE MACHINE

William W. Evans, Los Angeles, Calif.

Application October 6, 1937, Serial No. 167,615

11 Claims. (Cl. 128—54)

My invention relates to a massage machine of a type in which the massage is given by repeated beatings or a wiping action by a rapidly moving towel, cloth or other equivalent fabric. My construction is such that a person may stand adjacent the machine and be subject to the massaging action due to the towel or other fabric being rotated at a high speed and the ends thrown out by centrifugal action. There have been a number of machines designed as beaters and such like in which flexible material such as flexible arms, cords or the like are mounted in a holder and rapidly rotated, thus acting as beaters for cleaning carpets, rugs and the like, also attempts have been made to employ towels or other similar shaped fabric mounted in a holder and rotated whereby the ends are projected outwardly by centrifugal force and to utilize such a construction for drying the body in the so-called bathing machines. However my invention is intended more to give a massage and has the characteristics of a holder in which the towel may be readily inserted, such holder being mounted on a vertical rotating shaft whereby it may be raised and lowered to give a massage action from the head to the feet. The towel holder or carriage is mounted on the vertical shaft to be raised and lowered, there being a counter-weight so that the user of the machine may readily change the position as to height from the floor and thus the operator may readily regulate the portion of the body being subject to massage.

Another object and feature of my invention is a simple construction for varying the speed to have either a slow or a high rate of rotation of the towel carriage and hence the towel and to reverse the direction of rotation, also varying the speed in the reverse motion. My invention also comprehends the assembling and mounting of the machine whereby it may readily be located in the corner of a room and thus take up but little floor space having the vertical shaft mounted in an anti-friction bearing on the floor and connected to a friction type of gear drive for changing the speed and the reverse motion, the device being actuated preferably by an electric motor.

Another object and feature of my invention involves using the towel or other rapidly rotated fabric to give a medicated massage or rub. This is by impregnating the towel with a suitable liquid such as rubbing alcohol, witch-hazel or the like. The centrifugal action causes an outward flow of liquid towards the ends of the towel so

that the body is massaged by the damp towel. A more specific feature utilizes receptacles on the towel carriage for the liquid medicament. A towel holder clip assembly for supporting a towel has a perforated hollow rod or tube through which the liquid is discharged to the web of the towel and then flows outwardly under centrifugal action towards the ends of the towel.

My invention is illustrated in connection with the accompanying drawing, in which:

Fig. 1 is an elevation taken in the direction of the arrow 1 of Fig. 3.

Fig. 2 is a vertical section substantially on the line 2—2 of Fig. 3 in the direction of the arrows, certain of the various parts being shown in elevation and the floor support being omitted.

Fig. 3 is a horizontal section on the line 3—3 of Fig. 2 in the direction of the arrows, certain elements of the change and reverse speed friction drive being shown in plan.

Fig. 4 is a horizontal section on the line 4—4 of Fig. 2 in the direction of the arrows to illustrate mainly the towel holder clips.

Fig. 5 is a section on the line 5—5 of Fig. 2 through the counterweight pulleys.

Fig. 6 is a detail vertical section showing another form of the liquid medicament tank with a valve feed.

In my invention I employ a floor bearing 11 which has a receiving socket 12 with an anti-friction bearing therein for the rotatable tubular shaft 13. This shaft has a longitudinal spline 14. A supporting structure and drive assembly designated by the numeral 15 includes preferably a cylindrical case 16 from which arms 17 diverge and having attaching plates 18 to connect to two walls meeting for instance at a right angular corner. Such case has a bottom 19, a journal neck 20 with a bushing 21 fitted therein and held in place by a nut 22 threaded in the neck. A friction disc 23 has a collar 24 attached to the upper end of the shaft and thus transmits the rotational drive to the shaft.

This drive is by means of a drive shaft 25 which has one end journaled in a cup 26 at one side of the cylinder 16. The opposite end 27 is journaled in a bearing 28. A drive pulley 29 is connected to the outer end of the shaft and is actuated by a V shaped drive belt 30 operated from the drive pulley 31 on the shaft 32 of an electric motor 33, this motor being supported on the top or cover 34 of the case. The drive shaft as to the part inside of the case is preferably square or other non-circular shape and carries a longitudinally slidable friction wheel 40.

Such wheel is shown as having transverse ends 41, sloping sides 42, an annular groove 43, in which is fitted a friction tread ring 44. This may be of suitable material to develop friction against the disc 23. The friction wheel is moved longitudinally on the shaft 25 by means of a yoke 45 which has opposite arms 46 with inturned tips 47 to engage the plane ends 41 of the friction wheel. This yoke has a threaded hub 48 through which passes the screw 49 being mounted in journals 50 and 51 on opposite sides of the case. The screw has an operating hand wheel 52 with a handle 53 for ready rotation. A short arm 54 extends from the nut 48 in a direction opposite to the yoke arms and is provided with an eye 55 through which passes a guide rod 56, this rod being secured as indicated at 57 to opposite portions of the case 16. It will therefore be seen that by rotating the handle 53, the screw 49 is turned and thus moves the yoke assembly 45 longitudinally of the screw, the guide rod 56 and hence of the shaft 25. This develops a variable friction feed and also a reverse motion by passing the friction wheel from one side to the other 25 of the center of the friction disc and of the shaft. The towel carriage 60 has a hub 61 with a longitudinal keyway 62 fitted on the spline 14 and thus giving a driving relation with the rotatable shaft 13. The hub is provided with light weight 30 upper and lower flanges 64 and 63. A pair of hollow rods 66 positioned diametrically opposite connect the flanges 63 and 64, thus strengthening the carriage and forming part of a towel holder. The other portion of the towel holder 35 is a wire clip 70 which has a rod 71 illustrated as secured at 72 to the bottom flange 63, a reverse bend 73, a downwardly extending portion 74 parallel to the rod 71, terminating at 75 attached to the flange 63. The two portions 71 and 74 of this spring clip are placed closely contiguous to the rods or bars 66 but offset slightly to one side from the axial center of such rods. The towel 80 is threaded between the spring clip 40 and 74 of this spring clip are placed closely contiguous to the rods or bars 66 but offset slightly to one side from the axial center of such rods. The towel 80 is threaded between the spring clip and the rods 66, the center portion of the towel indicated at 81 encircling part of the hub 61. The towel may readily be inserted edgewise at 45 the reverse bend 73 of the spring clip. The towel is preferably stretched to have its end portions extend equi-distant from the center of the shaft. The balancing mechanism for readily raising 50 and lowering the carriage and towel includes a counterweight assembly 85. This comprises the tube 13 having a pair of opposite slots 86 with pulleys 87 fitted therein and mounted on journal pins 88. A counterweight 89 has a sliding fit 55 inside of the tubular shaft 13 and has two counterweight cords 90 extending upwardly from the weight over each pulley downwardly on the outside of the shaft and attached to the upper flange by eyes 91. By this construction a slight 60 pressure up or down on the towel carriage, that is, on the flanges 63 or 64, readily moves this carriage vertically on the shaft, the carriage remaining at any elevation. In the manipulation of this type of massage 65 machine it will be seen that the person taking the massage treatment may control the rate of rotation of the shaft as the hand wheel 52 and the handle 53 are in a convenient position to be 70 rotated. The electric motor may drive at a constant speed and the variable speed to the shaft 13 is developed through the friction gear drive. As is common with this type of drive, the direction of rotation may be reversed as above 75 set forth. The towel holds in proper position on

the towel carriage due to its friction attachment by the spring clip 70 adjacent the rod 66 and having the center portion pass around the hub 61. The ends of the towel are projected outwardly by a centrifugal force or action and thus give a massaging or beating action on the body of the operator. Manifestly the shaft 13 may be of such a height that the user may obtain a massage from head to foot and by turning the body can have a massage for the whole of the body. 10

In order to give a medicated massage by a liquid carried by the towel, I employ liquid reservoirs such as 95 secured to the upper flange 64 of the towel carriage. Each reservoir has a removable filler plug 96 and a connection to the hollow rod or tube 66. Such tube has perforations 97 on the side adjacent the web of the towel. A drain plug 98 extends through the lower flange 63 communicating with the tube 66 and may be used to drain the surplus liquid. By this construction the liquid such as rubbing alcohol, witch-hazel or the like is placed in the reservoir, the filler plug is then re-inserted. This liquid flows down in the tubes 66, being discharged at the perforations and therefore dampening the web of the cloth or towel secured in place by the towel holder including the towel holder clip. The moisture applied to the towel has a slow flowing action outwardly towards the ends of the towel by centrifugal action and hence dampens 25 the towel for giving this medicated massage. 30

In Fig. 6 I show an alternative form of reservoir construction in which a reservoir designated 105 is formed as a built-in construction or directly mounted on the upper flange 106, this being equivalent to the flange 64 of Fig. 2. Such reservoir preferably covers the complete top of the disc but has a central opening for the shaft 13. This reservoir has a cylindrical peripheral edge 107, a top 108. The feed tube for the medicament 109 extends downwardly from the 40 flange 106 and has perforations 110. A valve plug 111 is threaded in an opening in the top and has a bottom washer 112 which forms a seal with the top of the pipe 109, also an upper washer 113 which forms a seal with air inlet perforations 114. A filler plug 115 is provided. By this construction a relatively large quantity of liquid may be carried by the towel carriage. The feed may be regulated by the valve plug 111. When it is desired to shut off the feed entirely the plug 50 is screwed down tight. In this construction the counterweight 89 is designed to balance the carriage with the reservoir substantially filled with liquid. 55

Various changes may be made in the details of the construction without departing from the spirit or scope of the invention as defined by the appended claims.

I claim:

1. In a massage machine, a towel carriage having a central hub, a supporting structure forming a mounting for the hub whereby the carriage may be rotated on the axis of the hub, a pair of flanges extending outwardly from the hub, a towel holder including towel engaging elements extending between the two flanges and having means to hold and retain a flat strip of fabric forming the towel whereby on rotation of the carriage the ends of the towel outside of the 65 towel holder are thrown outwardly by centrifugal force. 70

2. In a massage machine as claimed in claim 1, the said towel holder including a pair of rods connecting the two flanges, a wire clip positioned 75

adjacent each rod, each clip having two parallel wires with a reverse bend, parallel portions being also parallel to the rod and the ends of the wire being attached to one of the flanges whereby the fabric strip is retained between the spring clip and the rod adjacent thereto.

5 3. In a massage machine as claimed in claim 1, the supporting structure for the hub including a hollow rotatable shaft with means forming 10 journals for said shaft, there being means to rotate the shaft, a counterweight in the shaft, the shaft being positioned vertical, counterweight cords connecting the counterweight and the towel carriage and operating through guides in 15 the shaft whereby the carriage may be raised and lowered on the shaft and retained at any desired position.

20 4. A massage machine comprising in combination an upper journal structure having means for attachment to a wall, a lower bearing adapted for attachment to the floor, a shaft rotatably mounted at its lower end in the bearing and its upper end in the journal structure, means to rotate the shaft from one end, a towel carriage connected to the shaft for rotational movement and for raising and lowering, said towel carriage having a pair of towel holders secured thereto, each holder being substantially parallel to the shaft and the holders being substantially on diamet- 25 rically opposite sides of the shaft, the holders having a construction to engage a flat strip of fabric forming a towel whereby on rotation of the shaft in the carriage, the end portions of the towel outside of the towel holders are thrown outwardly by centrifugal force.

30 5. A massage machine as claimed in claim 4, the shaft being hollow and having a pair of slots with guide pulleys positioned therein, a counterweight in the shaft, counterweight cords extending from the counterweight over the pulleys and connected to the carriage whereby the carriage is substantially balanced by the counterweight and may be raised and lowered on the shaft and retained in any desired position.

35 6. A massage machine as claimed in claim 4, the means to drive the shaft comprising a friction disc connected to the upper end of the shaft above the upper journal, a friction wheel rotatably and longitudinally movable on a shaft positioned above the friction disc, said latter shaft being transverse to the shaft having the towel carriage thereon, means to rotate the friction wheel shaft and means to move the friction wheel longitudinally of such latter shaft.

40 7. A massage machine as claimed in claim 4, the towel holder having a reservoir in its upper portion for a liquid medicament, one or both of the towel holders having a tubular rod with per-

forations connected to the reservoir for discharging the liquid medicament to the towel.

5 8. In a massage machine, a towel holding carriage having a central hub, means to rotate the carriage by the hub, towel holding clips and perforated tubes positioned spaced from the hub, the clips and the tubes providing towel engaging means and means to supply a liquid medicament to the tubes whereby the medicament flows from the tubes to the towel and is carried outwardly 10 in the towel by centrifugal force, the portions of the towel beyond the clips and the tubes being adapted to spread by a centrifugal action.

15 9. In a massage machine having a rotatable carriage having a reservoir and provided with upper and lower flanges, a tube extending between said flanges, a connection from the tube to the reservoir, a wire clip secured to one of the flanges and adapted to clamp a towel between the tube and the clip, the tube having perforations for discharging liquid medicament from the reservoir to the towel for outward flow under centrifugal force.

20 10. A massage machine comprising in combination a towel carriage, means to mount said carriage for rotation on its axis, said carriage having a plurality of towel holder clips positioned spaced from the axis of rotation of the carriage, said clips having means to engage a flat strip of fabric forming the towel whereby on rotation of the carriage the end portions of the towel projecting beyond the towel holder clip are thrown outwardly by centrifugal force, the carriage having a reservoir for liquid medicament, one element of the towel holding clips being hollow and having a connection to the reservoir with means to discharge the liquid medicament to the towel.

25 11. A massage machine comprising in combination a rotatable vertical shaft, a towel carriage having a hub slidably mounted on the shaft, means to counter-balance and to retain the carriage at a desired elevation on the shaft, an inter-engaging drive between the shaft and the hub, the carriage having a plurality of towel engaging clips spaced outwardly from the hub whereby a 30 flat strip of fabric forming a towel may be stretched between the clips and past the hub whereby the ends of the towel beyond the clips are forced outwardly by centrifugal force, at least one of the clips having a perforated tube, a reservoir mounted on the carriage and means to flow a liquid medicament from the reservoir to the tube and hence from the tube to the towel, such liquid being forced outwardly in the fabric at the towel ends by centrifugal force.
